UNITED STATES PATENT OFFICE.

PAUL SIFTROTT, OF BROOKLYN, NEW YORK.

FLOATING DEVICE FOR FLYING-MACHINES.

1,169,361.

Specification of Letters Patent. Patented Jan. 25, 1916.

Application filed August 7, 1915. Serial No. 44,146.

To all whom it may concern:

Be it known that I, PAUL SIFTROTT, a subject of the German Emperor, residing at Brooklyn, in the county of Kings and State of New York, have invented certain new and useful Improvements in Floating Devices for Flying-Machines, of which the following is a specification.

The present invention relates to flying machines and particularly to an attachment thereto consisting of a buoyant body, whereby when the flying machine descends on the water surface it may be kept floating.

The object of my invention is to produce such a construction which will allow the buoyant body of being collapsed when the machine is in the air, so as to present the least possible resistance to the air, and of being inflated when descending to the water surface, and of being revoluble.

Another object of my invention is to construct the device so that it can be easily and conveniently collapsed from the driver's seat.

With these and other objects in view, my invention consists in the construction, combination and arrangement of parts, as will be hereinafter fully specified and set forth in the appended claims.

In the accompanying drawings which form part of my invention and in which similar reference characters denote corresponding parts, Figure 1 is partly a front elevation and partly a vertical section of my device in inflated condition; Fig. 2 is a similar view of the device in collapsed condition; Fig. 3 is a sectional plan view of the device; Fig. 4 is a cross section on line 4-4 of Fig. 1; Fig. 5 is a vertical section through the plan of Fig. 3 as seen in direction of the arrows 5-5; Fig. 6 is an enlarged vertical section of an end part of my device and Fig. 7 is a vertical section on line 7-7 of Fig. 1.

In the drawing let F denote a part of a flying machine by which my device is to be carried by means of suitable members F', F''. My device consists of two buoyant inflatable bodies a, a'' which are identical in construction and operation.

I shall in the following describe in detail the construction of only one of the bodies. The inflatable buoyant body is substantially cylindrical and made of suitable waterproof and flexible material, stretched around and

fastened to a cylindrical skeleton frame, the periphery of which is formed of longitudinal ribs or braces b and whose end or side walls are formed of radial ribs or braces c and central rings d. The radial ribs c are 60 pivotally connected at one end, as c', to the peripheral braces b and at the other end, as c'', to the rings d. The members or rings d are revolvably mounted on sleeves e, f which are movably borne on a hollow shaft g 65 carried by the arms F', F'' of the flying machine and adapted to extend centrally and longitudinally through the body a. The shaft is closed up at its ends by caps g' and g'' and is provided on two diametrically opposed sides of its peripheral surface with longitudinal slots g' that extend from near the outer end to about the middle of the shaft. The outer sleeve e of each body a has fixed to its inner face a member or pin e' 70 which is adapted to extend vertically through the shaft, passing through and being movable within the slots g' thereof. This member is engaged by a rod h' that extends inwardly and centrally through the 75 hollow of the shaft and passes out of the body through the cap g' on the inner end of the shaft. The inner sleeve f on the other hand has attached to its outer surface members or rods h'' that in the example shown 80 are arranged vertically superposed and are connected to one another by a vertical pin h''. These members h' and h'' serve, as will be presently explained, for the manipulation of the sleeves e, f to move the same inwardly toward one another or to the middle of the shaft, when it is desired to collapse the body, or to move them outwardly or away from one another and toward the ends 85 of the shaft when it is desired to unfold and 90 inflate the body a.

As it was said above, the body a'' is identical in construction and operation with body a, the bar or rod i'' (Fig. 2) thereof being identical with the rod h' of the body a and 100 connected to the member or pin e' fixed to the outer sleeve e and the bars or rods i'', being fixed at one end to the outer face of the inner sleeve f of said body a'' and connected together at their opposite end by a pin i''. 105 The rods h', i'' are formed on their opposite faces to racks h and i respectively, which are adapted to meshingly engage a common pinion j carried by a rod R which by a steering wheel W can be controlled from the seat 110

of the operator. The rack h of the body a is furthermore connected to the pin i^3 of the rods i^2 of body a^2 and the rack i of body a^2 is connected to the pin h^3 of the rods h^2 of body a , so that by turning the pinion j in one direction the two sleeves e , f of each body will synchronously be moved toward one another, collapsing the frames and bodies a , a^2 , and by turning it in reverse direction the sleeves will move toward the ends of the respective bodies and unfold the same.

Now to allow of inflation and collapse of the bodies, I provide an air inlet for each, which may be formed by providing an air duct k in the arm F^2 communicating with the hollows of the shaft g from which the air will enter the bodies through the slots g^3 thereof. Thus when the bodies are to be collapsed and the sleeves e , f are moved inwardly, the air contained therein will be discharged through the slots g' , while when the bodies are inflated fresh air will be sucked in through the ducts k . The air inlets may be closed up by suitable valves (not shown) after the inflation of the bodies.

In the present application I have described and shown only one form of construction. It is evident that various modifications may be made in the details thereof without departing from the principle of my invention. I, therefore, wish it to be expressly understood, that I do not confine myself to the structure specified, but

What I claim and desire to secure by Letters Patent is:

35

1. The combination with a flying machine, of two inflatable buoyant bodies, a hollow shaft extending centrally through each body, sliding members on the ends of each shaft connected with their respective bodies, movable members extending centrally through said shafts and connected to said sliding members and common means operable from the driver's seat and serving to operate said movable members so as to collapse or inflate both said bodies simultaneously.

40

2. The combination with a flying machine, of two inflatable buoyant bodies, a hollow shaft extending centrally through each body, sliding members on the ends of each shaft, connected with their respective bodies, racks extending centrally through said shafts, each rack being connected at one end to one of the sliding members of its own shaft and at the opposite end to the sliding member of the other shaft and a pinion operable from the driver's seat and meshing with both said racks so as to collapse or inflate both said bodies simultaneously.

45

In testimony whereof I affix my signature in presence of two witnesses.

PAUL SIPTROTT.
